OCCUPANT PROPELLED ROUNDABOUT

William F. Behrens, Craigmont, Idaho

Application June 12, 1952, Serial No. 293,159

3 Claims. (Cl. 272—33)

1

This invention is an amusement device and it is one object of the invention to provide an amusement device for children and which will operate by using the manual energy of the children, and therefore will aid in the development of sound and strong bodies.

Another object of the invention lies in the provision of an amusement device which is adapted to carry a number of persons and be actuated by said persons.

Another object of the invention lies in the provision of an amusement device having a novel uni-directional rotatable motivating means for utilizing the physical energy of the occupants to activate the device.

Another object of the invention lies in the provision of an amusement device which is very easily constructed with a minimum number of parts and which is very effective for its purpose and not liable to break down or become inoperative.

These and other objects of the invention will become apparent during the course of the following description.

In the accompanying drawings, forming a part of this specification, and in which like numerals are employed to designate like parts,

Figure 1 is a plan view of the device embodying my invention,

Figure 2 is a transverse vertical cross section of the device,

Figure 3 is an enlarged fragmentary cross section of a portion of the supporting post and its companion parts,

Figure 4 is a horizontal cross section as at line 4—4 of Figure 2, and,

Figure 5 is a view as at line 5—5 of Figure 3.

Referring now more particularly to the drawing, the present invention is an amusement device of the "Merry-Go-Round" type and has a supporting base 10 having an annular tubular ring 11 divided in quarters by cross braces (not shown) of suitable material such as angle or channel iron and secured at their inner ends to a concentric upstanding vertical hollow post 12 braced by means of angled braces 13 secured at their inner ends to the post at a point above its lower end, and at their outer ends the braces are secured to the cross braces midway their lengths, thus providing a rigid supporting base.

A collar or ring 14 is secured about the post 12 at or above the point where braces 13 are secured and constitutes a support for annular rotatable platform 15. The platform is provided with a bearing housing 16 which has a bearing

2

receiving socket 17 open downwardly and in which a "timken" type or radial-thrust bearing 18 is confined. The bearing 18 fits about the post 12 and rests upon collar 14 to support the platform.

Radially extending fingers 19 are carried by the housing 16 and have transverse bolt holes for receiving bolts 20 which clamp angle iron frame legs 21 to the fingers. An annular tubular ring 22 is welded or otherwise secured about the outer ends of the legs 21. Other angle braces 23 are secured at their lower outer ends to the legs 21 substantially midway their lengths and extend upwardly at an inward incline where they are secured to a platform leveling ring 24 having an internal bearing sleeve 25 loosely fitting about post 12 for rotation thereabout. Seats 26 are carried by the platform and may be constructed as shown or of other ornamental design to delight the hearts of youngsters who play thereon. The seats shown have a foot support as 26' to provide purchase for manually motivating the platform. A covering 50 is applied over the platform frame to preclude the possibility of a child getting into the parts which move relative to each other where he might be injured.

The platform motivating means 27 is basically a number of radial levers 28 united at the center and having a depending stem 29 extending within post 12 and rotatable therein. The levers, as shown, are united by means of a relatively large disc 30 of concavo-convex shape and each lever is supplied with a wheel 31 to be grasped by a child seated on the companion seat. Stem 29 is secured to disc 30 centric thereof by means of a collar 31' bolted or otherwise secured to the disc 30 and also secured to the stem 29. The collar has a lower face 33 which rests upon a thrust bearing 34 which in turn rests upon the cover plate 35 of an over-running clutch housing 36 secured to the upper end of post 12, as by set bolts 37.

The over-running clutch consists of a number of tapered bearing receiving slots 38 disposed in the housing and about the stem 29 and springs 39 urge the balls into gripping relation with said stem so that stem 29 may be rotated counterclockwise, but not clockwise, therefore being uni-directional in its rotational movement. It can easily be seen that a person sitting on one of the seats and pulling a lever to rotate the stem counterclockwise, will cause the clutch to lock and the platform will rotate about the post 12. However, when pull is released, the motivating means may rotate freely clockwise. The

platform may thus be rotated by successively pulling and releasing the pressure on the motivating means.

Having thus described my invention, I claim:

1. An amusement device comprising a vertically supported non-rotatable hollow post; said post having an annular collar spaced upwardly from its lower end; a radial-thrust bearing encircling said post and supported on said collar; an annular platform having a centric bearing housing rotatably supported on said bearing for rotatably supporting said platform; a platform leveling ring carried by the platform and spaced upwardly from said bearing and in encircling relation to said post; a bearing sleeve within said ring and rotatable about said post; a plurality of seats carried by said platform; a downwardly curved concavo-convex disc disposed in a substantially horizontal plane concentric with said post; a depending stem secured to the disc and extending downwardly into said post; a thrust bearing intermediate said post and stem for rotatably supporting the disc; a uni-directional over-running clutch uniting said post and stem; and means on the disc adapted to be grasped by occupants of the seats, whereby manual pressure rotates said platform.

2. In an amusement device having an annular platform adapted to carry a number of persons and rotatably supported about a non-rotatable hollow post; platform motivating mechanism comprising a disc having a coaxial depending stem loosely fitting within said hollow post; said disc having a plurality of radially extending levers secured thereto and carrying wheels on their outer ends; a uni-directional over-running clutch secured to the upper end of said post and operably connected to said stem; and a thrust

bearing intermediate said post and disk to rotatably support the disk.

3. In an amusement device having a supporting base including a vertically disposed hollow post and a manually operable motivating means rotatably carried by the post and operably connected therewith by means of a uni-directional over-running clutch; a rotatable platform comprising a collar secured about the post upwardly spaced from its lower end; a radial-thrust bearing snugly encircling said post and supported upon said collar; a downwardly open bearing housing rotatably supported upon said bearing; radially extending integral fingers circumferentially spaced about said housing; legs secured one to each said finger and extending axially therefrom; an annular ring secured to and uniting the free ends of said legs; angle braces secured to the legs intermediate their lengths and extending upwardly at an inward incline; the upper ends of said braces being secured to a ring encircling said post upwardly spaced from said collar; a bearing sleeve coaxial with said ring and journaled on said post; and a covering overlaying the angle braces and the outer end portions of the legs.
